UNITED STATES PATENT OFFICE.

CLAUDIUS EDLUND, OF BROOKLYN, NEW YORK.

COMBINED IMPLEMENT FOR TAILORS' USE.

SPECIFICATION forming part of Letters Patent No. 293,857, dated February 19, 1884.

Application filed August 6, 1883. (No model.)

To all whom it may concern:

Be it known that I, CLAUDIO EDLUND, of Brooklyn, in the county of Kings and State of New York, have invented a new and Improved Combined Chalk-Knife, Waste-Chalk Receiver, Pin-Cup, and Paper-Weight, of which the following is a full, clear, and exact description.

Reference is to be had to the accompanying drawings, forming part of this specification, in which similar letters of reference indicate corresponding parts in both the figures.

Figure 1 is a plan view of my improvement. Fig. 2 is a sectional end elevation of the same, taken through the line *x x*, Fig. 1.

The object of this invention is to promote the convenience of tailors and others using chalk and pins and having to secure their work in place by weights.

The invention consists in a combined chalk-knife, waste-chalk receiver, pin-cup, and paper-weight constructed with a base, a hollow body having top and bottom openings and recessed top, and provided with outwardly-inclined projecting jaws, recessed to receive knives having corrugated faces, the said bottom opening being closed by a stopper, as hereinafter fully described.

A represents the base of the implement, which can be made rectangular in form, as shown in Fig. 1, or of any other desired shape.

B is the body of the implement, the lower part of which is contracted into a small stem, and is connected with the base *A*. The base *A* and body *B* are preferably cast in one piece, but may be cast separate and screwed together or otherwise connected. The body *B* may be made oval or of any other desired form, and upon the middle part of its top are formed two projections or jaws, *C*, which incline from each other, leaving a *V*-shaped opening between them. The top of the body *B*, around the jaws *C*, is recessed to form a cup, *D*, to receive pins. The inner sides of the jaws *C* are recessed to form seats to receive the knives *E*, which are secured in place by screws or other suitable means.

The knives *E* are made in the form of plates with corrugated faces, the said corrugations being made in the form of ratchet-teeth with sharp edges to adapt them to shave off the sides of the edges of tailors' chalk or crayon and give the said edges a *V* form.

The body *B* is made hollow to form a receiver, *F*, for the waste chalk, and has an opening, *G*, in its top between the jaws *C*, so that the fine chalk shaved off by the knives *E* will slide down the grooves of the said knives *E* and fall into the receiver *F*. In the bottom of the body *B* is formed an opening, *H*, extending down through the base *A*, and closed at its lower end by a slide, *I*, or other suitable stopper, so that the waste-chalk receiver can be readily emptied when desired.

The lower side of the base *A* is recessed to form a space, *J*, for the stopper *I*, and in the upper side of the said base is formed a recess, *K*, to serve as a receptacle for pieces of chalk or other desired objects.

The implement is made sufficiently heavy to adapt it to serve as a weight to hold papers or work in place upon a desk, table, or bench.

Having thus described my invention, I claim as new and desire to secure by Letters Patent—

1. A combined chalk-knife, waste-chalk receiver, pin-cup, and paper-weight constructed substantially as herein shown and described, and consisting of the base *A*, the hollow body *B*, having top and bottom openings and recessed top, and provided with outwardly-inclined recessed jaws *C*, the corrugated knives *E*, and the stopper *I*, as set forth.

2. In a combined chalk-knife, waste-chalk receiver, pin-cup, and paper-weight, the body *B*, made hollow, having top and bottom openings and a recessed top, and provided with outwardly-inclined recessed jaws *C*, substantially as herein shown and described, to adapt the said body to receive chalk-shaving knives, and to serve as a waste-chalk receiver and as a pin-cup, as set forth.

3. In a combined chalk-knife, waste-chalk receiver, pin-cup, and paper-weight, the combination, with the outwardly inclined and recessed projecting jaws *C*, of the hollow body *B*, and of the knives *E*, having corrugated faces, substantially as herein shown and described, whereby the chalk can be readily brought to an accurate *V*-shaped edge, as set forth.

CLAUDIO EDLUND.
